(57) **CLAIM**

The ornamental design for a shaft and gear housing as shown and described.

DESCRIPTION

FIG. 1 is a first perspective view of the design;
FIG. 2 is a second perspective view of the design;
FIG. 3 is a first side elevational view thereof;
FIG. 4 is a second side elevational view thereof;
FIG. 5 is a top plan view thereof;
FIG. 6 is a bottom plan view thereof;
FIG. 7 is a third side elevational view thereof; and,
FIG. 8 is a fourth side elevational view thereof.
In the drawings, the broken lines depict portions of the shaft and gear housing that form no part of the claimed design.
